HOLDER FOR ATTACHED COLLARS

Neal I. Paulsen, Minneapolis, Minn.

Application February 15, 1946, Serial No. 647,678

1 Claim. (Cl. 223—83)

1

My invention relates to holders for attached collars, and has for its object to provide a cheap and inexpensive member which can be applied within the collar band of a laundered shirt and which not only will hold the collar in position but will effectively prevent the collar being crushed or bent when the same is stored in suitcases, drawers or the like.

Heretofore laundries have been accustomed to apply to the front part of the collar a form of device which is applied to the portion of the collar under the tabs. While such a device holds the front of the collar and the tabs in position it has no effect upon the back part and sides of the collar, which, particularly when carried in suitcases or the like, frequently becomes crushed and bent so as to be unsightly when worn.

I have discovered a very simple arrangement of flexible but edgewise rigid band which may be applied within the collar and so that its edges will extend outside of the plane of the top of the collar, whereby the collar will at all times be protected against compression which would crush or distort the collar.

It is a principal object of my invention, therefore, to provide a flexible but edgewise rigid band. This band will be of such length relative to the circumferential extent of the inner part of the collar that when inserted within the collar there will be a loop turned in and the band will press against the inner side of the collar wall, thus receiving and resisting any pressure which could otherwise be transmitted to the collar itself.

It is a further object of my invention to provide such a band with means for attachment to the fold of the collar whereby it will be anchored in position within the collar.

It is also an object of my invention to use the band bent in the manner heretofore described for insertion within the collar when properly folded, without any means of attachment to the collar other than the expanding force of the folded band inside the collar, and its frictional engagement with the inner collar wall.

The full objects and advantages of my invention will be made to appear in connection with the following specification, and the novel features of the invention by which the aforesaid advantageous results are obtained will be particularly pointed out in the claim.

In the drawings illustrating an application of my invention in some of its forms:

Fig. 1 is a plan view of a freshly laundered folded shirt having my holding means applied thereto.

2

Fig. 2 is a sectional view taken on line 2—2 of Fig. 1 and on a larger scale showing the manner in which the collar holder is positioned within the collar.

5 Fig. 3 is a plan view of the form of collar holding strip employed in Figs. 1 and 2.

Fig. 4 illustrates a strip similar to that of Fig. 3 but without any means of attachment to the collar itself yet otherwise in the same position as the strip of Fig. 1.

Fig. 5 illustrates a plan view of a freshly laundered shirt showing another means of putting the collar protecting strip in position within the collar.

10 Fig. 6 illustrates the type of collar strip employed in Figs. 4 and 5.

Fig. 7 is an edge view of the holder strip of Figs. 3 and 6.

15 As illustrated in Fig. 1 a shirt 7, of standard or customary construction, is shown folded in the usual manner after laundering, with the collar tabs 8 and 8a turned down on the front of the shirt so as to leave the overlapping band 9 and the button hole 10 therethrough between the tabs 20 8 and 8a.

25 In the form of Figs. 1, 2 and 3, a band 11 of paper board material which is springy and edgewise rigid and noncollapsible from transverse strain is provided with angularly disposed notches 12 and 12a, Fig. 3, and this band is shown positioned in the shirt collar band in Fig. 1.

30 To effect the positioning of the holder and protector 11 within the band of the collar 22, the ends 20 and 21 are brought together leaving the protector band bulged backwardly as indicated in dotted lines at 23. The two slots 12 and 12a are pushed down over the front or folded collar band each as clearly shown in Fig. 2 and also as indicated in Fig. 1. The bulge 23 is then pushed 35 forward and depressed within the collar to form inside the collar band an inner loop 13 and two outer loops 24 and 25.

35 These loops are pressed down within the collar band 22 and released. They will then with their natural spring expand outwardly, holding the shirt collar band 22 as indicated in Fig. 1.

40 Also the upper edge 26 of the holder 11, as clearly shown in Fig. 2, extends above the upper edge 22 of the folded collar indicated generally 45 by the numeral 16. This extended portion is shown at 27 immediately adjacent the highest part of the edge of collar 22 and is indicated as above dotted line 28, which shows the line of the collar 22 from its highest point adjacent the part 50 marked 27 to the tabs 8 and 8a.

In the form of the invention illustrated in Fig. 4, the protective holder 14 of Figs. 6 and 7 is employed. Here the ends 30 and 31 of said strip are cut square, without any slots similar to slots 12 and 12a. The application of the holder is the same as in Fig. 1 excepting that in this form the ends 30 and 31 are brought together at the front of the shirt band inside the collar band as shown in Fig. 4, with a center loop 13a and side loops 24a and 25a.

The contact of the edges 30 and 31 will resist the expansive force of the protective holder 14 and hold the same in position extending above the upper edge 22 of the collar about as indicated in the dotted line 28 of Fig. 2, excepting that the protective member is entirely inside the band 9.

A very good result is also obtained in the application of the protective band in the form of Fig. 5. Here the end edges 30 and 31 of protective strip 14 are placed in contact and in parallel turned inwardly, as shown at 32 of Fig. 5.

In this form the center 33 of the band will contact the front shirt band 9 on the inside thereof and there will be two loops 34 and 35 without any intervening loops such as 13. Again, however, the spring of the paper board strip 14 will hold the collar stretched in position and will extend above the upper edge 22, and by its edgewise stiffness and rigidity will prevent distortion of the collar.

The advantages of my invention will appear in connection with the detailed description heretofore given. In all of the forms there is a strip of spring paper board so held within the inner limits of the shirt collar that the collar itself is maintained expanded and the protective card extends above the upper or outer edge of the collar itself and has sufficient rigidity to resist pressure toward the collar, even when very considerable, and thus maintains the collar at all times in its finished condition after laundering, undistorted by any external pressures toward the edge of the collar.

The primary advantage of my invention is, therefore, that it does maintain the laundered collar throughout its extent, not merely just adjacent the tabs, in the form in which it has been put by laundering, undistorted from any cause.

It is a further great advantage of this invention that it can be manufactured at very low cost, considerably lower than devices now employed, which tend to hold only the collar tabs in position and which do not protect the back portions of the collar.

Another great advantage of this invention re-

sides in the fact that the protective collar holder may be applied to the collar at the laundry with very great ease and with consumption of only a very small amount of time.

A further advantage of my invention, particularly when referred to the methods and devices heretofore employed in holding the tabs of the collar from the front, comes from the fact that operators place these under-tab members in position while the shirt is what is known as "green," that is while substantially dry yet is not perfectly dry. Under these conditions the application of the old form of device has a tendency to leave the collar tabs twisted out of position and frequently with deforming wrinkles and frequently leaves it in that condition, while with my invention the application does not effect the position of the tabs at all nor produce wrinkles, no matter how "green" the shirt may be at that time.

I claim:

A collar protecting device which comprises a band of springy paper board, said band being considerably longer than the inside dimension of a laundered collar and being wider than the greatest width of the laundered collar, angularly disposed slots formed in the band adjacent each end adapted to be slipped over the front collar band between the collar tabs, said device being adapted to be positioned within the laundered collar and when so positioned being formed with loops engageable with the respective sides of the collar and by the spring of said loops holding the collar in formed position as laundered and protecting it from distortion through application of outside pressure or force.

NEAL I. PAULSEN.
